CHARLES H. SMITH, OF BOSTON, MASSACHUSETTS.

Letters Patent No. 85,970, dated January 19, 1869.

IMPROVEMENT IN CHURN AND BUTTER-WORKER COMBINED.

The Schedule referred to in these Letters Patent and making part of the same.

To all persons to whom these presents may come:

Be it known that I, CHARLES H. SMITH, of Boston, in the county of Suffolk, and State of Massachusetts, have made a new and useful invention having reference to Churns and Butter-Workers; and I do hereby declare the same to be fully described in the following specification, and represented in the accompanying drawings, of which—

Figure 1 is a side elevation, and

Figure 2, a vertical section of a churn and butter-worker made in accordance with my invention.

Figure 3 is a vertical section of the churn, it being taken through the fastenings by which the two parts of the barrel of the churn are connected.

Figure 4 is a top view of the churn-dasher.

Figure 5 is a top view of the butter-worker dasher.

Figure 6 is a top view of the cover of the butter-worker.

The tub or reservoir of the churn is formed in two separate portions, A B, one (A) of which rests directly on the top of the other (B) or, in other words, on an annulus, C, of India rubber, or other proper yielding substance, capable of making a tight joint between the parts when the upper one is drawn down upon such annulus.

A flange, a, projecting from the lower portion, B, encompasses the lower part of the upper portion, A, of the churn-reservoir.

The lower part, B, of the churn-reservoir is provided with a bottom, b, and rests directly upon a platform or stand, D, it being held thereon, and in connection with the upper part, A, by two screw-rods, E E, which extend upward from staples b' b', inserted in the platform.

The rods go through ears, c c, extending from the lower part of the portion A of the churn-reservoir, and receive screw-nuts, d d, which, by being screwed down against the ears or washers f f, laid thereon, serve, with the rods and ears, to hold the parts A and B in connection.

There are a cover, g, and a dasher, G, to the portion A, the rod of the dasher being extended through the said cover. The dasher is to be used for churning cream when in the churn.

Besides the churn and its fastening, as described, there is applied to the platform, by means of a lever, H, and a post, I, a butter-worker dasher, K.

The post is jointed to the platform, so as to be capable of being turned horizontally, and of being moved or vibrated both toward and away from the churn.

The said post at top is also hinged to one end of the lever, such lever also being hinged to the top of the rod h of the butter-worker dasher K.

There is arranged concentrically on the rod h, a cap or cover, L, which fits on the top of the lower part, B, of the churn, and is provided with a bar, i. This bar extends diametrically across the said cover, and projects from it in opposite directions, in manner as represented. At each of its ends the bar is notched to receive one of the screw-rods E E, which, with their nuts, serve to fasten the cover tightly down upon the top of the part B.

The dasher-rod h, I usually apply to the lever in a manner to enable the dasher K to freely revolve while being worked up and down in the part B by the lever.

After the churn may have been used for the purpose of making butter, the buttermilk should be removed from it, and the upper part, A, and its dasher, should be removed from the lower portion, B. Next, the butter-worker dasher should be introduced into the part B, and the cover L confined to the part B, by means of the connection-rods and nuts and the cross-bar i.

By laying hold of the lever and pressing it downward, the dasher K will be forced down upon the butter, which, on being squeezed between the dasher and the bottom of the tub or part B, will be caused to flow up through the openings of the dasher, and up on its top. Next, by drawing up the dasher, the butter may be pressed against the cover, so as to be again squeezed through the dasher. These operations of the dasher being continued, will cause the buttermilk to be expressed from the butter.

By having the churn-reservoir made in two parts, A B, as described, and provided with means, as explained, for connecting them together, we are enabled to separate the upper portion from the lower, so as to admit of the latter being employed with the auxiliary cover and dasher, and its post and lever, as a butter-worker, the churn-reservoir, when composed of the two parts A B, being too large for such purpose.

I make no claim to a churn-reservoir consisting of a single tub or vessel, B; but

I claim, as my invention, the following, viz:

The churn-reservoir, as composed of the two portions A B, and their fastening or connecting-devices, made and applied substantially as specified.

Also, the combination of the auxiliary cover L and dasher K, and its operative lever H, or mechanism, with the platform D, or its equivalent, the two parts A B of the churn-reservoir, and the connection-devices, substantially as described.

CHARLES H. SMITH.
